UNITED STATES PATENT OFFICE

171,390

MODEL STAGECOACH BODY FOR COASTER WAGONS OR SIMILAR ARTICLE

Arthur A. Ebert, Tucson, Ariz.

Application July 10, 1953, Serial No. 25,873

Term of patent 14 years

(Cl. D34—15)

To all whom it may concern:

Be it known that I, Arthur A. Ebert, a citizen of the United States and a resident of the city of Tucson, in the county of Pima and State of Arizona, have invented a new, original, and ornamental Design for a Model Stagecoach Body for Coaster Wagons or Similar Article, of which the following is a specification, reference being had to the accompanying drawing, forming a part thereof.

On the drawing:

Figure 1 is a perspective view of the model stagecoach body for coaster wagons or similar article, showing my new design; and

Figure 2 is a top plan view thereof.

The opposite side, not shown, has substan-

tially the same appearance as the side shown in Fig. 1.

The coaster wagon body is a complete article, and the wheels, axles, and connecting structure shown in broken lines in Fig. 1 are for illustrative purposes only.

I claim:

The ornamental design for a model stagecoach body for coaster wagons or similar article, as shown and described.

ARTHUR A. EBERT.
